AUDIO-VISUAL CARTRIDGE FOR A STRIPFILM PROJECTOR

Frank C. Badalich, Chicago, Ill., assignor to
Bell & Howell Company, Chicago, Ill.

Filed Sept. 24, 1970, Ser. No. 25,183

Term of patent 14 years

Int. Cl. D16—05

U.S. Cl. D61—1

Fig. 1.

Fig. 2.

Fig. 3.

FIG. 1 is a front, top and right side perspective view of an audio-visual cartridge for a stripfilm projector showing my design, the left side being substantially a mirror image thereof;

FIG. 2 is a front elevational view thereof; and
FIG. 3 is a rear elevational view thereof.

I claim:

The ornamental design for an audio-visual cartridge for a stripfilm projector, as shown and described.
